UNITED STATES PATENT OFFICE

ANDREW M. ANDERSON, OF NEWFIELD, NEW JERSEY

SELF-SEALING JAR

Application filed July 28, 1928. Serial No. 296,027.

My invention relates to self sealing jars of the general type used for preserving fruit and the object of the invention is to provide a jar in which the sealing means is more efficient and the sealing and opening of the jar more conveniently and more speedily effected than with jars heretofore used.

The invention consists of a jar having a countersunk seat at its upper end and a cover 10 adapted to rest in said seat, said cover being provided with an annular groove containing a sealing member and a second groove adapted to lie opposite the upper end of the jar and to receive therein a prying instrument for 15 moving the cover.

In the drawing, Figure 1 is a top view of a jar and cover embodying my invention and Figure 2 a central vertical section of the same.

20 Referring to the drawing, the numeral 1 indicates the body of the jar which is reduced in size adjacent the top and provided with an annular internal shoulder 2 upon which the cover may rest. The jar extends above 25 the shoulder providing a flange 3 which encircles the cover when in position for use. The cover 4 has an annular groove 5 adjacent its base, preferably rectangular in shape, and an annular groove 6 between groove 5 and the upper surface of the cover. The upper wall of groove 6 preferably slopes upwardly and the part of the cover above the groove provides a substantial flange 7 which extends above flange 3 and is spaced from the 35 top thereof.

An elastic ring 8 is seated in groove 5 which is sufficiently deep to firmly hold the ring, and the jar is sealed by pressing the cover, with the ring, downwardly until it contacts with 40 shoulder 2.

The cover may be removed by inserting any object adapted to function as a lever into groove 6 and using the top of flange 3 as a fulcrum.

45 The construction of the jar and sealing member associated therewith may be changed in various details within the scope of the invention as hereinbefore set forth and herein-after claimed.

50 I claim:—

1. A jar having a substantially cylindrical neck with an annular shoulder spaced from the top of the neck, a cover proportioned to sit upon the shoulder and to substantially fill and extend above the top of the neck, said cover having an annular groove, a gasket seated in the groove and making sealing contact with the neck above the shoulder, said cover having a second groove located in part above the top of the neck. 55

2. A jar having a substantially cylindrical neck with an annular shoulder spaced from the top of the neck, a substantially cylindrical cover proportioned to sit upon the shoulder and to substantially fill and extend above the top of the neck, said cover having an annular groove, and a gasket seated in the groove and making sealing contact with the neck above the shoulder, said cover having a second groove located in part above the top of the neck. 60

3. A jar having a substantially cylindrical neck with an annular shoulder spaced from the top of the neck, a cover substantially filling the neck and seated upon the shoulder and having a circumferential groove, and a gasket seated with its major part within the groove and making sealing contact with the inner walls of the neck above the shoulder, said cover having also a groove in part above the top of the neck. 65

70 In testimony whereof I have signed my name to this specification.
